UNITED STATES PATENT OFFICE.

HARRY D. CAHILL, OF BOSTON, MASSACHUSETTS.

ELECTRIC-CLUSTER-LAMP BODY AND SHADE-HOLDER.

1,353,563.

Specification of Letters Patent. Patented Sept. 21, 1920.

Application filed January 26, 1920. Serial No. 354,172.

To all whom it may concern:

Be it known that I, HENRY D. CAHILL, a citizen of the United States, residing at Boston, county of Suffolk, State of Massachusetts, have invented a certain new and useful Improvement in Electric-Cluster-Lamp Bodies and Shade-Holders, of which the following is a specification, reference being had therein to the accompanying drawings.

One object of the invention is to provide a portable electric lamp body adapted for use with a cluster of lamps. Another object of the invention is to provide the cluster lamp body with a shade support for use in combination with a shade for a center lamp and side lamps. Another object of the invention is to provide the cluster body with interchangeable means whereby it is adapted for use either with side lamps alone without a center lamp, or for use in combination with a center lamp and side lamps. Another object of the invention is to provide a shade holder for use with a low-down shade so called, when the side lamps alone are used. Another object is to provide the lamp with means for supporting a shade when the center lamp is used with the side lamps.

The invention will be fully understood when taken in connection with the accompanying drawings, and the novel features thereof will be pointed out and clearly defined in the claims at the close of this specification.

In the drawings, Figure 1 is a view in elevation partly in section of a lamp body, together with a cluster of lights in combination with a reflector, reflector supporting plate, lamp shade and shade holder, embodying the invention.

Fig. 2 is a view in elevation of the lamp body shown in Fig. 1.

Fig. 3 is a plan view of the lamp body.

Fig. 4 is a detail view of the reflector supporting member shown in Fig. 1.

Fig. 5 is a detail view showing the method of attaching to the lamp body the lamps composing the cluster.

Fig. 6 is a view in elevation of the wire shade holder shown in Fig. 1.

Fig. 7 is a plan view of the wire shade holder shown in Fig. 6.

Fig. 8 is a view in elevation partly in section showing the wire shade holder together with an auxiliary shade holder for use in supporting a lamp shade centrally of the lamp body.

Fig. 9 is a view in elevation of the auxiliary shade holder shown in Fig. 8.

Fig. 10 is a view in elevation partly in section showing the lamp body together with a cluster of lights in combination with a shade supporting member, the indirect light being detached from the lamp assembly.

Fig. 11 is a view in elevation of the shade supporting member shown in Fig. 10.

Fig. 12 is a plan view of the shade supporting member of Fig. 11.

Referring now to the drawings, 1 represents a lamp body which is shown without the ordinary supporting base but is adapted to be attached to any suitable form of support, the said body portion 1 preferably being internally screw-threaded in its lower end portion 2, so that it may be screwed to the standard of the support.

The upper part of the body has an outwardly flaring cup-shaped portion 10 to form a seat for the holder plate on which the shade holder which surrounds the reflector is seated. When a center light is used with the cluster as shown in Fig. 1 the said holder plate comprises a saucer-shaped base 8 having a flaring portion 9, a central aperture, and an upwardly extending screw-threaded tubular portion 3 rising from the periphery of the aperture in the base 8. The lamp body is provided with a lamp socket 29, which extends up through the aperture in the base 8 into the tubular portion 3 of the reflector supporting plate. The base 4 of an electric light bulb 5 is inserted loosely down through the tubular member 3 of the reflector supporting plate and is screwed into the socket 29. The base 8 of the reflector supporting plate is seated upon the flaring upper end 10 of the lamp body which is shown in Fig. 1. The rim 11 of the flaring portion of the lamp body is curved to form an annular internal 100

groove to receive the lower end of the shade holder.

The reflector 7 is preferably flared upwardly on an ogee curve and its lower end 5 is formed with an annular base portion 6 which is internally screw-threaded to fit the exterior screw threads of the upwardly extending portion 8 of the reflector supporting plate. The reflector is screwed onto the 10 outside of the tubular member 3.

In order to support a shade as well as lock the parts together, I provide a skeleton frame, preferably made of wire (see Figs. 1, 6 and 7), which serves to lock the 15 reflector supporting plate 8 in position on its seat in the body of the lamp. This wire frame is preferably of the general contour of the reflector 7 but is of larger diameter so as to surround the reflector. It comprises a 20 plurality of upright rib portions 17, preferably four in number arranged 90° apart from each other, and preferably bent to the general shape shown in Figs. 1 and 6. Each 25 wire 17 is bent at its lower end to form a loop 18, which as shown bulges slightly outward and serves as a locking lug, as will be hereinafter explained. A 30 ring 19 runs through the eye of said lug 18 forming an annular bottom for the shade holder and serves as a tie to unite 35 together the lower ends of the rib portions 17. It is welded or otherwise permanently secured to the lug portions 18 so that they will not slip. Preferably there is also provided 40 a wire ring 20 which is welded to the ribs a short distance above the ring 19 and rests upon the upturned ends of the lug portions 18 of the ribs, as shown in Figs. 1 and 6.

There is also preferably provided another 45 wire ring 22 which encircles the four rib members 17 at some point intermediate the upper and lower ends as shown in Figs. 1, 6 and 7, and is welded or otherwise secured thereto.

The upper end of each rib member 17 is 50 preferably bent over to form a substantially horizontal arm 23 terminating in a U-shaped hook 24. The purpose of the U-shaped hooks is to enable them to support the ring 55 of a shade, as will be hereinafter described. Preferably also at the end of the upright portion of the rib 17 where it is bent to form the arm 23 it is twisted to form a loop or eye 25 for the purpose of connection with an auxiliary wire frame to support a flat-topped shade, as will be hereinafter described. A wire ring 26 encircles the ribs 55 near their upper ends just below the said loops 25, and is secured to said ribs by welding or other suitable means.

The upper edge or rim 11 of the body 1 is formed with four notches 27 corresponding in number and spaced apart from each other corresponding with the spacing of 60 the loop or lug portions 18 of the wire ribs

17, so that the wire cage may be assembled with the body 1 by seating the wire cage down on top of the body with the said lug portions 18 in alignment with the several notches 27 in the rim 11 of the body 1. 70 These notches admit the loop or lug portions 18 down into the annular groove within the rim 11, then by turning partially around on its axis so as to bring the lug portions 18 into the portion of the groove intermediate 75 the notches, the said wire frame is securely locked against withdrawal from the body of the lamp except by continuing the rotation to bring the lugs 18 again into alignment with the notches. When the wire frame is 80 thus assembled with the base, the said lug portions 18 are seated upon the flaring rim 9 of the reflector supporting plate 8 and hold the said plate to its seat on the flaring rim 10 of the lamp body. Thus the reflector 85 supporting plate 8, the reflector 7, the wire frame, and the lamp body 1 are all rigidly locked together.

The U-shaped hooks 24 on the ends of the arms 23 may serve as supports for the supporting ring of a shade, if desired.

The construction thus far described so far as relates to the reflector and the means of locking together the lamp body, reflector and reflector supporting plate, forms the 95 subject matter of a companion application by me, and is claimed therein.

In addition to the features above described, the body 1 is formed so that it can be used with a cluster of lamps as shown in 100 Figs. 1, 5 and 10; that is, in addition to the center lamp 5 it is adapted to have connected therewith two or more side lamps 30 which have suitable connection with the body 1 at the sides of the lamp body. To 105 this end the lamp body is provided with apertures 31 in the sides thereof, into each of which is secured the threaded end 32 of the stem 33, which is in swivel connection with a socket member 34 adapted to receive 110 the base of the lamp 30 in the usual manner. The swivel connection of the lamp socket with the stem 33 consists of forming the stem 33 with an annular groove 35 which is engaged by a screw 39 mounted in the 115 socket member 34. The socket member 34 may be turned on its axis so as to bring the lamp at varying angles of inclination, as shown in Fig. 1. It may be held in its adjusted position by the screw 39. These side 120 lamps 30 will extend outside of the ribs 17 of the wire cage.

A shade 37 either of silk or porcelain, or other suitable material, may be hung from the hooks 24 of the wire frame, so as to surround the said side lamps 30. This shade 37 is formed with a ring 38 which is received into the hooks 24 to support the shade.

The ribs 17 of the shade holder as well as the side of the reflector have an incurve 130

about midway of their length, so that the side lamps may be turned up into a more upright position if desired.

The arms 23 being of wire may easily be bent to either bring them around closer to the top ring of the frame or to extend more directly outward so as to adapt them to shade ring tops of varying sizes; or the arms 23 may be bent upward or downward to change the elevation.

I also provide an auxiliary wire frame to support a shade centrally of the lamp body. This support is separable from the main wire frame and is shown in detail in Fig. 9. In this case the auxiliary holder comprises a small central ring 40 with which are connected four radiating wire arms or ribs 41, said wire ribs 41 being bent to form eyes at one end through which the ring 40 passes, the outer ends of said ribs being bent downward to form downward projecting fingers 42 which pass through the eyes 25 formed in the ribs 17, so as to connect the auxiliary wire frame with the main frame. Intermediate the downwardly extending portions 42 and the radiating portions 41 of said ribs, each of said ribs is bent around to form a loop 43, and through the eyes of these loops there is run a wire ring 44 which is welded or otherwise secured thereto, and which prevents the spreading apart of the members 41 and holds them in fixed relation to each other.

At the junction of the arms 23 with the ribs 17 the eyes 25 are formed by looping the wire as already described. The auxiliary shade holder frame above described consisting of the two rings 40 and 44, and the arms or rib portions 41, is assembled with the main shade holder frame by inserting the downwardly projecting fingers 42 through the eyes 25 as shown in Fig. 8.

A shade 45 having a top 46 is assembled with the auxiliary wire frame. Any suitable clamping means may be employed; that shown in the drawings is as follows:— The top 46 of the shade is formed with a central aperture 47. A bolt 48 is passed up through the ring 40 and thence up through the said aperture 47 in the top of the shade, and then a clamping nut 49 is screwed onto the upper end of the bolt 48 and set up to clamp the top of the shade and the ring 40 firmly together. Preferably washers 51 and 52 are employed for bearing surfaces on the under side of the shade top 46 and on the upper side of the head of the bolt 48.

This shade should preferably have spread enough to cover the full cluster of lights the same as the shade 37 in Fig. 1 incloses said cluster of lights.

If it is desired to dispense with the central indirect light and reflector by dispensing and to use only the side lights 65 turned at a downward inclination, the same

body 1 may be employed as in the several forms already described, and in this case the wire frames may both be dispensed with. Means for connecting the shade with the lamp body may be provided with locking mechanism of the same character and working on the same principle as that in which the wire frame which supports the indirect reflector and the ring topped shade is locked to the lamp body. This form of construction is shown in Figs. 10, 11 and 12. In this case the reflector supporting plate 3 shown in Figs. 1 and 4 may be entirely dispensed with. The rim 11 will be formed with notches 27 similar to those shown in Figs. 2 and 3. The shade holder 53 is bell-shaped as shown in Figs. 10 and 11, and is provided with lugs 54 on its periphery for the purpose of engaging with the notches 27 corresponding in function to the lugs 18 on the ribs of the first described wire shade holder; that is the shade holder 53 will be assembled with the lamp body by setting the shade holder down upon the lamp body with the said lugs 54 in alignment with the notches 27, and then giving a partial turn to the shade holder so as to bring the said lugs 54 around into the annular groove within the rim 11 intermediate the notches. The lower edge of the shade holder 53 will rest upon the flaring rim portion 9^a if the plate 8^a is used; when such plate is not used it will simply rest on the flaring rim 10 of the lamp body.

The shade 55 is similar to the shade 45 shown in Fig. 8 and already described, and has a top 56 which is united with the shade holder 53 in a very similar manner to that in which the shade 45 is united to the auxiliary cage shown in Fig. 8; that is the shade top 56 is formed with a central aperture and the shade holder 53 is also formed with a central aperture in its top. The two are united by means of a bolt 57, said bolt passing through the apertures in the shade top 56 and in the shade holder 53, and are clamped together by means of a nut 58 screwed onto the end of the bolt 57. Preferably washers 60 and 61 are employed to form the bearing surfaces of the shade and shade holder.

It will thus be seen that the same lamp body and the same general principle of uniting together the shade holder and the lamp body are employed in all the several different forms. If the indirect light is desired to be used together with a cluster of lamps comprising a central light and side lights as shown in Fig. 1, the lamp body is adapted for that purpose as already described with reference to Figs. 1, 2, 3, 4 and 5, the wire frame which serves as a shade holder being locked into combination with the lamp body by means of the lugs formed by the eyes 18 engaging with the groove 130

formed in the rim 11 of the lamp body as already described, and being fitted to be engaged or disengaged, as desired, by means of the notches 27 and the rotation of the 5 wire frame on its seat. The said wire frame serves as a shade holder if a shade 37 is desired in addition to the reflector.

In such case the shade will have a ring top so as to allow the light from the central 10 lamp to be reflected upwardly. If, however, the center light is to be dispensed with and the side lights only are used, then it will not be necessary to use the indirect reflector 7 and the shade 45, such as shown in Fig. 8, 15 may be employed and connected with the main shade holder by means of the auxiliary shade holder and the bolt shown in Fig. 8.

If the indirect lamp together with its reflector are to be dispensed with and dis- 20 mantled, the wire frames are both removed, and a shade 55 together with the bell-shaped shade holder 53 are employed, the shade holder 53 being locked to the body 1 in a similar manner to that in which the wire 25 frame is locked to the body. This gives the effect of a low hanging shade. It will thus be seen that the same lamp body may be used interchangeably with any of the several forms of shade holders and shades.

30 What I claim is:—

1. An electric lamp body having in combination therewith a shade holder, said shade holder and lamp body having interlocking connections, whereby the shade 35 holder may be locked to the lamp body, and an auxiliary shade holder adapted to be seated upon the top of said first shade holder, one of said shade holders being formed with a plurality of fingers and the 40 other of said shade holders being formed with a plurality of coöperating finger holes with which said fingers are adapted to engage to hold the two shades together.
2. An electric lamp body having an upper 45 end formed with a rim having an annular groove and a plurality of notches extending from the upper edge of the rim down into said annular groove, a lamp shade holder which is adapted to fit into said annular 50 groove, and having a plurality of lugs which prevent the shade holder from being inserted into the said groove except when the lugs are alined with the notches, said lugs being so spaced apart with relation to the notches 55 that when the lugs are brought into alinement with the notches, said shade holder may be rotated to turn the lugs into the groove out of alinement with the notches and lock the shade holder and the body together, said shade holder being formed with a plurality of eyes at its upper end for engagement with an auxiliary shade holder, in combination with an auxiliary shade holder to be seated on the top of said first shade 60 holder, and having a plurality of fingers 65

which are adapted to engage with the said eyes in said first shade holder.

3. An electric lamp body having a cup-shaped upper end, a lamp shade holder mounted thereon formed as a skeleton cage, 70 having a plurality of upright rib portions, the upper ends of said ribs also having arms provided with hooks to detachably hold the ring of a lamp shade, said holder being formed with eyes for detachable engage- 75 ment with an auxiliary shade holder, in combination with an auxiliary shade holder having a ring formed with a plurality of fingers which detachably engage with the eyes formed in said first shade holder. 80

4. An electric lamp body having a cup-shaped upper end, a lamp shade holder mounted thereon formed as a skeleton cage, 85 having a plurality of upright rib portions, the upper ends of said ribs also having arms provided with hooks to detachably hold the ring of a lamp shade, said holder being formed with eyes for detachable engage- 90 ment with an auxiliary shade holder, in combination with an auxiliary shade holder having a ring formed with a plurality of fingers which detachably engage with the eyes formed in said first shade holder, a small ring centrally arranged with relation to said first ring of the auxiliary shade 95 holder and having ribs radiating from said small central ring and connected with said outer ring, and means for clamping a shade to the small center ring of said second 100 holder.

5. An electric lamp body having an upper end formed with a ring having an annular groove and a plurality of notches extending from the upper edge of the rim down into said annular groove, a wire lamp shade holder formed with wire upright ribs, and wire ring portions connecting the said wire ribs both at the top and at the bottom, said rib portions being bent near the lower ends to form loops which are adapted to engage with said notches, and which when the holder is rotated engage with the groove in the lamp body to lock the shade holder to the lamp body, the upper ends of the rib portions being extended and bent to form 110 upwardly extending arms with hooks to receive and hold the ring of a lamp shade. 115

6. An electric lamp body having an upper end formed with a ring having an annular groove and a plurality of notches extending from the upper edge of the rim down into said annular groove, a wire lamp shade holder formed with wire upright ribs, and wire ring portions connecting the said wire ribs both at the top and at the bottom, said rib portions being bent near the lower ends to form loops which are adapted to engage with said notches, and which when the holder is rotated engage with the groove in the lamp body to lock the shade holder to 120 125 130 135

the lamp body, the upper ends of the rib portions being extended and bent to form upwardly extending arms with hooks to receive and hold the ring of a lamp shade, said 5 outwardly extending arms being bent to form eyes for engagement with an auxiliary shade holder, in combination with an

auxiliary shade holder having a ring formed with a plurality of downwardly extending fingers which are adapted to engage with 10 said eyes formed in the arms of said first shade holder.

In testimony whereof I affix my signature.

HENRY D. CAHILL.
